UNITED STATES PATENT OFFICE.

JAMES J. TRACY, OF CLEVELAND, OHIO.

MANUFACTURE OF HATS.

1,214,845.

Specification of Letters Patent.

Patented Feb. 6, 1917.

Application filed April 3, 1913. Serial No. 758,564.

To all whom it may concern:

Be it known that I, JAMES J. TRACY, a citizen of the United States, and a resident of Cleveland, county of Cuyahoga, and 5 State of Ohio, have invented a new and useful Improvement in the Manufacture of Hats, of which the following is a specification, the principle of the invention being herein explained and the best mode in which 10 I have contemplated applying that principle, so as to distinguish it from other inventions.

In the manufacture of straw hats as heretofore carried on, the usual procedure is to 15 sew the braid to the shape desired, whether consisting of the crown and the brim joined, or made separately; thereupon such hat shape is sponged with liquid glue or size and dried in a drying chamber, where a 20 temperature of 100° F. or higher has to be maintained in order to effect the drying with sufficient expedition; from said drying chamber the hats or parts thereof are taken in a very much distorted condition, and 25 steamed over open steam boxes to soften them; and then they are finally blocked by being pressed over interiorly heated forms of the desired shape, being worked down by hand, and pressure blocks being applied to 30 the outside, until they have set, it being understood that the form blocks are maintained at such a temperature as to dry the glue in the straw and thus cause the latter to retain the final desired shape.

35 The object of the present invention is to provide a method of procedure and apparatus for use in the same, whereby the foregoing operations in connection with the manufacture of straw hats may be very 40 materially shortened and in part entirely eliminated, thereby materially quickening the process of manufacture and at the same time rendering the work pleasanter and easier for the operators. To the accomplishment of the foregoing and related ends said invention, then, consists of the steps hereininafter fully described and particularly pointed out in the claims. It should also be explained that the apparatus aspect of the 45 invention forms the subject matter of a separate divisional application filed December 29, 1916, Serial No. 139,461.

The annexed drawing and the following description set forth in detail certain means

and one mode of carrying out the invention, 55 such disclosed means and mode illustrating, however, but one of various ways in which the principle of the invention may be used.

In said annexed drawing:—

Figure 1 is a side elevation and part sectional view of an apparatus adapted for the carrying on of my improved method of manufacture; Fig. 2 is a plan view of a portion of such apparatus; and Fig. 3 is a perspective view of an element removed from 65 the rest of the apparatus.

Describing first of all the apparatus utilized in carrying out my improved method of manufacture, such apparatus is relatively simple, consisting of a table or work-bench 1, that carries a series of apertured base-plates 2, upon which the hat molds 3, whether for the crown of the hat, as shown at the right of Fig. 1, or the brim of the hat, as shown at the left, or the whole hat, 70 are designed to rest, such whole hat or part thereof being termed indifferently a hat-part in the present specification. These molds may be made out of plaster of Paris and the portion thereof designed to receive 75 the hat part is provided with a number of closely arranged perforations. An annular sheet 4 of soft rubber, or like packing material, may be interposed between each base-plate 2 and the mold resting thereon, if 80 found necessary to form a tight seal between the two, such seal being desirable for reasons that will presently appear. Connected with the central aperture in each base-plate is the flaring, or funnel-like, upper end 5 of a duct 6, the lower end of which is connected to a manifold or main duct 7 leading to a suction fan 8. The latter may be operated by a motor 9, as shown, or any other suitable driving mechanism. 90

Removably supported within the conical or funnel-like upper end 5 of each duct 6 is a cup 10 with flaring walls of the form shown in Fig. 3, having lugs or arms 11 extending laterally from its edge, so as to support the cup in the position shown at the left in Fig. 1, just below or in the opening in the base-plate 2. In such opening a ring 12 of beveled shape is preferably inserted, the inner edge of the ring forming a flange 100 for the opening in the base, that extends within the edge of the cup. This ring may be supported either from the sheet of pack-

ing, where such is used, or directly from the base 2.

Below the cup, at a convenient point in each duct, is a valve 13 preferably of the 5 familiar slide type, operable by a handle 14.

In utilizing the foregoing apparatus in carrying out my improved method, the hat-parts are taken just as they come from the sewers, and are fitted over the molds 3 in- 10 tended for their reception, the valves 13 in the corresponding ducts being closed. Thereupon, by opening any particular valve, a sufficient suction is created within the corresponding mold to hold the hat-part firmly 15 thereon, whether crown or brim, and while it is thus held snugly onto the mold, the glue, or sizing, is applied in liquid form with a sponge. Any excess of the glue that is drawn through the hat and through the 20 mold is caught by the cup 10 in the throat of the duct, the ring 12 below the mold serving to guide the particles of glue into said cup. The cup being removable may be taken out and emptied as occasion demands. It may 25 also be desirable to locate a similar separator in the discharge duct 17 leading from the fan 8, in order to intercept any particles of glue that may be carried along with the draft of air past the cup 10.

30 The current of air, drawn through the hat resting on the mold after the application of the glue, very quickly dries the latter and obviously leaves the hat of exactly the desired form. There is no chance for the hat- 35 part to buckle or warp, this being very apt to occur, particularly at the peak of the crown, when the hat is subjected to heating, as is necessary in the prevailing method of manufacture. Aside from this and other 40 advantages pertaining to the betterment of the product, the simplification in manufacture permits a very considerable increase in rate of production, one man doing as much as three men under the old conditions, while 45 owing to the absence of all heating and steaming steps the comfort of the operator is much greater.

Other modes of applying the principle of my invention may be employed instead of 50 the one explained, change being made as regards the steps herein disclosed, provided

those stated by any one of the following claims or their equivalents be employed.

I therefore particularly point out and distinctly claim as my invention:—

55

1. The method of manufacturing hats of straw or like material, which consists in applying liquid glue or size to the hat-part; then drying the same by passing air there- 60 through; and maintaining such part in the form desired during such drying.

2. The method of manufacturing hats of straw or like material, which consists in applying liquid or size to the hat-part; then 65 drying the same by passing air there- through; and holding such part, during such drying, against a mold of the form desired.

3. The method of manufacturing hats of straw or like material, which consists in applying liquid or size to the hat-part; then 70 drying the same by passing air there- through; and holding such part, during such drying, against a mold of the shape desired by the same air used in drying.

4. In the manufacture of hats of straw 75 or like material, the steps which consist in placing the hat-part with one side in contact with a mold of the form desired; applying liquid glue to such part while thus in contact with such mold; and passing a current 80 of air through such part and mold to hold the former in place against the latter and dry the glue thus applied.

5. In the manufacture of hats of straw or like material, the steps which consist in plac- 85 ing the hat-part over a perforated mold of the form desired so as to have one side in contact with such mold; applying liquid glue to such part while thus in contact with such mold; and simultaneously drawing a 90 current of air through such part and mold, whereby the former is held in place against the latter, such current of air being continued long enough to dry the glue thus applied.

95

Signed by me, this 31st day of March, 1913.

JAMES J. TRACY.
